GAME BOARD

Donald J. Munson, Jr., 1311 W. 24th St.,
Minneapolis, Minn. 55405

Filed Mar. 12, 1973, Ser. No. 340,230

Term of patent 3½ years

Int. Cl. D21—01

U.S. Cl. D34—5 SS

FIG. 1 is a perspective view of the game board design and illustrating the front and one side wall;

FIG. 2 is a top plan view of the game board design as illustrated in FIG. 1;

FIG. 3 is a front elevational view of the design, with the rear elevational view being identical thereto;

FIG. 4 is a side elevational view of the design, with the opposite side being identical; and

FIG. 5 is a bottom elevational view of the game board design.

I claim:

The ornamental design for a game board, substantially as shown.
